(No Model.)

E. CHILDREN.

CULTIVATOR.

No. 334,641.

Patented Jan. 19, 1886.

UNITED STATES PATENT OFFICE.

EDWIN CHILDREN, OF DUNLEITH, ILLINOIS.

CULTIVATOR.

SPECIFICATION forming part of Letters Patent No. 334,641, dated January 19, 1886.

Application filed September 9, 1885. Serial No. 176,602. (No model.)

To all whom it may concern:

Be it known that I, EDWIN CHILDREN, of Dunleith, in the county of Jo Daviess and State of Illinois, have invented a new and useful Improvement in Cultivators; and I do hereby declare that the following is a full and exact description of the same, reference being had to the accompanying drawings, and to the letters of reference marked thereon.

10 My invention relates to that class of farming implements known as "sulky-cultivators," and embodies improvements upon the implement described and shown in Patent No. 159,500, granted to me February 9, 1875, which is for a shifting contrivance for varying the line of a pivoted draft-pole and the plow-beams.

15 The present improvements relate more particularly to means for raising, lowering, and adjusting the plow-beams to the lever for shifting and varying the line of the draft-pole and plow-beams, and to a friction-roller on the rear end of the draft-pole; and the novelty consists in the construction, arrangement, and combination of these and other parts of the machine, 20 all as more fully hereinafter described, and pointed out in the claims.

For a better understanding of the parts in detail, attention is invited to the accompanying drawings, in which—

25 Figure 1 represents a perspective view taken from the rear of my improved cultivator; Fig. 2, a top plan view of the same; Figs. 3 and 4, details of certain parts. Fig. 5 is a detail showing the connection of the plow-beams and swing-arms to the sway-beam, and Fig. 6 a detail of the shifting-lever and its fulcrum.

Like letters refer to corresponding parts in the several views.

30 A denotes a rectangular frame mounted upon two wheels, B B, and composed of two front and rear pairs of horizontal cross-bars, a a and a' a', respectively, secured at their ends to the two intermediate side bars, b b, which run parallel at right angles to the former, and are connected at the rear ends to another cross-bar, c.

35 C is the draft-pole, pivoted centrally between the front pair of cross-bars, a a, of the frame A, as shown at c', and provided on its rear end with a friction-roller, c'', which travels between the rear pair of cross-bars a' a', and renders it easier to shift or change the line of draft.

D is the driver's seat, supported in the rear of the frame A by a single curved spring, or two stout springs, d d, secured at the front 55 ends to the rear pair of cross-bars a' a'.

E E are the plow-beams, pivoted at the front ends to a sway-beam, E', which is pivotally supported by the parallel swing-arms F F, pivotally connected at their rear ends to the 60 cross-bar c of the frame A, and extended in front of the sway-beam E' far enough to bring the rollers e e upon the front ends to a bearing upon the lower one of the front pair of cross-bars, a a. The draft-pole C is provided at its 65 rear end with a rigid arm, e', and a link, f, connects this arm to one of the swing-arms F, and another link, f', connects this arm e' to an arm, g', of the lever-pin g, so that the motion of said draft-pole, imparted by the lever 70 G, is communicated to the swing-arms and to both plow-beams, as in my other patent, except by a few additions and a change in the arrangement of the lever G, the shifting of 75 these parts is rendered more convenient and easier in this machine.

The pin g, to which the lever G is attached, has loose bearings in a bracket, h, secured to the rear cross-bar c of the frame A, and is cast or otherwise provided on its upper end 80 with a ring, g', having on its inner circumference two recesses, i i, each adapted to receive the pin i' at the inner forked end of the lever G. This lever is made telescopic, having an inner handle, G', whereby the driver can 85 transform the machine into a walking-cultivator, and extend this lever to such a length that, when walking, he can operate the same to change the line of draft as conveniently as when riding, and by means of the two recesses 90 i i in the ring on the upper end of the lever-pin g the point at which the lever is attached can be changed by merely disengaging its pin i' from one of said recesses and engaging it with the other, so that a change in the length 95 of the lever-arm shall not affect the power necessary to move the lever.

Upon each of the plow-beams is secured a ratchet-frame, H, in the form of a segment, with which engages a pawl, k, of a lever, H', pivoted 100 to the side of its ratchet-frame. Each lever H' has a hooked arm, k', to which is attached one end of a chain, k'', the other end passing down under a pulley, k'', mounted on the plow-

beams, and up to the end of a crane, I, where it is attached to a hook on the same. Each crane is suspended over the cross-bar e by engagement with a casting or socket, I', pivoted 5 one to each swing-arm F, and said cranes are adapted, as shown, to be readily disengaged from their supports. Each casting or socket I' has bearing upon an elastic support, m, which may be either a leaf, spiral, or rubber 10 spring; but preferably a metal leaf-spring secured to the swing-arms, whereby an elastic or springy motion is given to the plow-beams, and considerable aid is furnished in the raising of the same by the pawl-and-ratchet 15 contrivances.

By pivotally attaching the plow-beams and the cranes to the movable portion of the frame the lateral movement of the same is much easier accomplished, for all that the operator has 20 to do is to raise the beams a trifle, and then by the use of the lever shift the draft-pole, and the same movement is transmitted to the plow-beams and their attachments, whereas in other cultivators, where the beams are rigidly 25 attached to the frame, a much greater power is required to shift them laterally.

Having thus described my invention and enumerated some of its advantages, what I 3c claim, and desire to secure by Letters Patent, is—

1. The combination, in a cultivator, of a movable frame comprising a sway-beam and a

pair of swing-arms pivoted at one end and provided with friction-rollers on the opposite end, a pair of vertically-adjustable plow-beams 35 pivoted to said sway-beam, a pivoted draft-pole with a friction-roller on its rear end, a telescopic shifting - lever, and intermediate link - connections between said draft - pole, swing-arms, and shifting-lever, substantially 40 as and for the purposes set forth.

2. In a cultivator, the combination, with the movable frame comprising the swing-arms F F and sway-beam E', of the pivoted plow-beams E, ratchet-frames H, secured upon the same, 45 levers H', with pawl k, and arm k', cranes I, and the intermediate connections with said levers, and sockets I', pivoted to the swing-arms F and elastically supported upon the same, substantially as described. 5c

3. In a cultivator, the combination, with the movable frame comprising a sway-beam, E', and a pair of swing-arms, F F, of the pivoted draft-pole C, having arm e', links f and f', lever-pin g, having arm g' and recessed ring g', and telescopic lever G, substantially as and for the purposes set forth. 55

In testimony whereof I affix my signature in presence of two witnesses.

EDWIN CHILDREN.

Witnesses:

WILLIAM GRAHAM,
MONROE M. CADY.
